(74) **Attorney, Agent, or Firm:** Banner & Witcoff, Ltd.

(57) **CLAIM**

The ornamental design for a measuring device as shown and described.

DESCRIPTION

FIG. 1 is a perspective front view of a measuring device showing my new design;

FIG. 2 is a perspective rear view thereof;

FIG. 3 is a front view thereof;

FIG. 4 is a rear view thereof;

FIG. 5 is a left side view thereof;

FIG. 6 is a right side view thereof;

FIG. 7 is a bottom plan view thereof;

FIG. 8 is a top plan view thereof;

FIG. 9 is a perspective front view of the measuring device of FIGS. 1-8 being unshaded;

FIG. 10 is a perspective rear view thereof;

FIG. 11 is a front view thereof;

FIG. 12 is a rear view thereof;

FIG. 13 is a left side view thereof;

FIG. 14 is a right side view thereof;

FIG. 15 is a bottom plan view thereof; and,

FIG. 16 is a top plan view thereof.
